COMBINED CLIP BOARD AND PEN HOLDER OR THE LIKE

Noboru Wakai, Tokyo-to, Japan, assignor to Dai Nihon Bungu Kabushiki Kaisha, (also trading as the Japan Stationery Co., Ltd.), Tokyo, Japan, a corporation of Japan

Filed Sept. 13, 1966, Ser. No. 3,849

Term of patent 14 years

(Cl. D74—2)

FIG. 1 is a perspective front view of a combined clip board and pen holder or the like embodying the new design;

FIG. 2 is an elevational view of the left side thereof; FIG. 3 is an elevational view of the rear thereof; and FIG. 4 is a perspective bottom view thereof.

I claim:

The ornamental design for a combined clip board and pen holder or the like, substantially as shown and described.
